US0D1021641S

(12) **United States Design Patent** (10) **Patent No.:** **US D1,021,641 S**
(45) **Date of Patent:** **** Apr. 9, 2024**

(54) **PARKING PAY STATION**

(71) Applicant: **IPS Group Inc.**, San Diego, CA (US)

(72) Inventors: **David William King**, Rancho Santa Fe, CA (US); **Choor-Hong Tan**, Epping (AU); **Derek Wu**, Strathfield (AU); **David Andrew Jones**, Beecroft (AU)

(73) Assignee: **IPS GROUP INC**, San Diego, CA (US)

(**) Term: **15 Years**

(21) Appl. No.: **29/839,309**

(22) Filed: **May 19, 2022**

Related U.S. Application Data

(62) Division of application No. 29/700,891, filed on Aug. 6, 2019, now Pat. No. Des. 955,231.

(57) **CLAIM**

The ornamental design for a parking pay station, as shown and described.

DESCRIPTION

FIG. 1 is a top, front, right perspective view of a parking pay station, showing our new design;

FIG. 2 is a top, back, left perspective view thereof;

FIG. 3 is a front elevational view thereof;

FIG. 4 is a back elevational view thereof;

FIG. 5 is a left side elevational view thereof;

FIG. 6 is a right side elevational view thereof; and,

FIG. 7 is a top plan view thereof.

The even dashed broken lines shown in the drawings represent portions of the parking pay station that form no part of the claimed design.
